UNITED STATES PATENT OFFICE.

JOHN LUNDIE, OF NEW YORK, N. Y.

TIE-PLATE.

1,065,696.

Specification of Letters Patent. Patented June 24, 1913.

Application filed September 14, 1912. Serial No. 720,345.

REISSUED

To all whom it may concern:

Be it known that I, JOHN LUNDIE, a citizen of the United States, residing at New York, in the borough of Manhattan, county 5 and State of New York, have invented certain new and useful Improvements in Tie-Plates, of which the following is a specification.

This invention relates to improvements in 10 tie-plates for railroads.

The objects of the invention are to provide a tie-plate which in use will locate all the bearing surfaces in such position as to be normal to the line of the thrust of the 15 wheels or wheel load, and also to provide a tie-plate so constructed as to allow the rail to adjust itself easily under a load without coming in contact with a sharp angle and which will bite into the tie to prevent the 20 plate from slipping endwise.

Other objects are to provide a durable, practical and efficient tie-plate.

These being among the objects of my invention, the same consists of certain features 25 of construction and combinations of parts to be hereinafter described and then pointed out in the claims with reference to the accompanying drawings showing a suitable embodiment of the invention, and in 30 which—

Figure 1 is a transverse section on the line 1—1, Fig. 3, looking in the direction of the arrow, and showing a spiked rail and tie-plate with a fragment of a wheel passing 35 over the rail; Fig. 2 is a transverse section, illustrating the same parts taken on the line 2—2 Fig. 3, and looking in the direction of the arrow; Fig. 3 is a side elevation of a spiked rail and tie-plate showing a fragment 40 of a tie in section, and Fig. 4 is a perspective view of the preferred construction of tie-plate.

Referring to the drawings, the tie 10 supports the tie-plate 11 which in turn supports 45 the rail 12, and 13 indicates a car-wheel. A standard car-wheel is provided with a tread having a 1 in 20 bevel and as the webs of the rails usually stand vertically, a side thrust is produced on the rails which is open 50 to more or less objection. It has been proposed to provide a tie-plate with an inclined surface on which the base of the rail rests so that the rail shall be inclined, but so far as I know, no one has ever suggested the arrangement of all the bearing surfaces so that 55

they shall be normal to the line of wheel load. To this end my improved tie-plate is constructed as follows: The upper surface or rail seat 14 of the tie-plate 11 is inclined transversely for substantially its entire 60 width. The lower surface is constructed with a series of steps, which series extends transversely of the tie-plate, so as to provide bearing surfaces 15, 15^a, 15^b and so on. Said surfaces are stepped relatively to each other 65 and extend longitudinally of the tie-plate as indicated by dotted lines in Fig. 4. The surfaces 15, 15^a and 15^b or as many bearing surfaces as there are on the underside of the tie-plate, are not only parallel with each other but are in planes parallel with the inclined upper surfaces 14 of the plate. The stepped surfaces 15, 15^a and 15^b and so on, are joined by curved surfaces 16 so as to 70 avoid sharp corners. It will be seen that the 75 series of steps is substantially parallel with the transverse axis of the tie-plate but that the individual surfaces are not parallel therewith. The bearing surface 17 of the head of the rail 12 will likewise be parallel 80 with the before-mentioned surfaces 14 and 15, 15^a and 15^b. The tie-plate near one edge is provided with a well-known rail-retaining flange 18, and the plate and rail are secured in position in the usual manner by means of 85 spikes such as 19 and 20 which pass through suitable openings in the tie-plate.

The principle of the described construction is more clearly illustrated in Fig. 1. In this figure the vertical is indicated by *a*, 90 while *b* indicates the line of stress which is normal to all bearing surfaces including the surface 17 of the rail head, 14 of the tie-plate and the stepped surfaces 15, 15^a and 15^b and so forth at the underside of the tie-plate. As compared with a standard wheel, the inclination of the dotted line *b* to the vertical is 1 in 20. The horizontal is indicated by *c* but the bearing surface 17 corresponds with the inclination of the bevel of 100 the car-wheel if it be standard, that is to say, 1 in 20, and this inclination to the horizontal is indicated by *d*. The series of stepped surfaces 15, 15^a, 15^b and so forth at the underside of the tie-plate are normal to the line of 105 stress for the purpose of neutralizing the side thrust, due to the beveled bearing of the wheel, which is a valuable feature in connection with the construction described. The curves connecting said lower bearing 110

surfaces are for the purpose of preventing the breaking of the fibers of the tie such as

10. Such tie must obviously be of yielding material such as wood.

5 Another highly important feature of the present invention consists in a slight camber of the tie-plate which extends from end 21 to end 22 and which is longitudinal to the line of the track for the purpose of

10 preventing the rail in its deflection under a wheel load from coming in contact with a sharp edge and at the same time decreasing the span of the rail deflected, while acting in the nature of a continuous beam.

15 Preferably, and for the purpose of cambering the tie-plate, the same is bent up from a metal plate, and in such manner that the convexity of the plate is at the upper surface 14 and corresponds with the extrados

20 of an arch while the incurve is at the lower surface and corresponds with the intrados of an arch. A further advantage of the camber is that it allows a slight bite of the ends 21 and 22 of the plate into the tie 10, thus preventing the plate from crawling or slipping endwise in the length of the rail. It will be seen that the rail rests on the convex summit of the upper surface 14

so as to produce a more suitable bearing 30 surface than if the summit were angular, and thus shortens the rail span without the rail in its deflection being in danger of coming in contact with one of the sharp ends of the plate.

35 A further advantage in the present invention is that the improved tie-plate produces its own seat in the tie.

40 The plate may be made of steel and bent in a bull-dozer and punched at the same operation. It is clear that the illustrated form of the invention is susceptible of

modification, and that I am not limited to details of construction.

Having thus described my invention, what I claim as new is:—

45 1. A tie-plate for railway rails, the same having an upper rail seat normal to the line of thrust of the standard coned tread car-wheel, and lower stepped surfaces parallel with said seat.

50 2. A tie-plate for railway rails, the same having an upper rail seat normal to the line of thrust of the standard coned tread car-wheel, and lower stepped surfaces parallel with said seat, said surfaces being joined by curves.

55 3. A tie-plate for railway rails, the same having an upper rail seat normal to the line of thrust of the standard coned tread car-wheel, and lower stepped surfaces parallel with said seat, said plate having a camber which is longitudinal to the line of track.

60 4. The combination of a tie-plate having an upper rail seat which is normal to the line of thrust of the standard coned tread car-wheel and lower stepped surfaces parallel with said seat, and an inclined rail resting on said seat.

65 5. The combination of a tie of yielding material having no previously formed seat, a tie-plate constructed to produce its own seat in said tie by biting into it, and a rail, all of the bearing surfaces of which parts, that is to say said tie-plate and rail, are 70 normal to the line of thrust of a standard coned car-wheel.

75 JOHN LUNDIE.
